UNWINDING THREAD

James Burrel Parker, Rome, Ga., assignor to
 Tubize Chatillon Corporation, a corporation of
 Delaware

Application June 28, 1940, Serial No. 342,845

6 Claims. (Cl. 242—129)

This invention relates to the unwinding of thread from a yarn package or the like, and has for its object the provision of certain improvements in unwinding thread from yarn packages. The invention aims more particularly to provide an improved practice and apparatus for unwinding rayon thread from initially unsupported annular packages or cakes of bobbin-spun or pot-spun yarn onto cones, spools, or the like.

Various forms of rayon cone winding machines are in use, differing somewhat in construction according to the particular demands made upon them and the particular purposes for which they are intended. In general, these machines comprise an appropriate stationary support for the yarn package, a cone winding spindle and cooperating traverse guide for drawing the thread off the package and winding it into the contemplated cone, and intermediate devices for conditioning and tensioning the thread. The present invention is particularly concerned with the yarn package support for such machines, and contemplates an improved yarn package support upon which initially unsupported yarn packages may be readily mounted and operatively supported with sufficient tension to assure complete unwinding of all the yarn without sloughing off and without injury to the yarn.

In the production of rayon thread or yarn, it is now common practice to subject the yarn to certain treatments, particularly preshrinking and drying, in the form of an unsupported package. To this end the yarn is wound upon some form of collapsible bobbin, and is removed from the bobbin and subjected to the contemplated treatment operations in the form of a substantially annular package or cake, without any supporting means. The present invention is especially adopted for unwinding the thread of such an unsupported package and winding it into cones, spools or other types of finished commercial packages or "put-ups".

In accordance with the present invention, the substantially annular yarn package is placed upon a supporting arbor positioned within the package and tightly pressing against the interior surface thereof, and as the thread is unwound from the package, in the course of cone winding, the pressure exerted by the arbor against the interior surface of the package progressively decreases. The arbor, in its preferred form, is made of two relatively movable parts, one of which is secured to a stationary base and the other is arranged to slide on the base towards and away from the part secured to the base. A

spring normally biases the movable part of the arbor to its operative position most remote from the other part of the arbor with a force that varies inversely as the distance between the two parts. A manually operated lever moves the two parts of the arbor, against the tension of the spring, into their contacting operative positions for placing the yarn package thereon at the start of the unwinding operation.

10 The invention will be better understood from the following description taken in conjunction with the accompanying drawings, in which

Fig. 1 is a side elevation, partly in section, of one unit of a cone winding machine embodying the invention,

Fig. 2 is a side elevation of the improved yarn package support of the invention with the two relatively movable parts of the arbor closed to receive a yarn package, which is shown thereon,

Fig. 3 is a front elevation of the yarn package support,

Fig. 4 is a top plan of the yarn package support with the two relatively movable parts of the arbor in their contacting operative positions, i. e. closed,

Fig. 5 is a top plan of the yarn package support with the two relatively movable parts of the arbor in their operative positions most remote from one another, and

Fig. 6 is a detail view of the stop-motion device.

The cone winding machine comprises a plurality of longitudinally adjacent units such as shown in Fig. 1 of the drawings. In this figure, the substantially annular and initially unsupported yarn package 10 is shown operatively mounted on the expanding two-part supporting arbor of the invention. The thread or yarn 11 is drawn from the package, in the unwinding and coning operation, and wound into the form of a cone on a rotating spindle 12. The thread passes, from the package 10, through guide eyes 13, over an oiling or other appropriate conditioning roll 14, through a guide eye 15 and tension device 16 of the finger or washboard type, and thence onto the cone winding spindle 12, which is driven by any of the well-known means.

The various units of the cone winding machine are mounted alongside one another on a main frame 17. A longitudinally extending cake board 18 is secured to the lower part of the frame 17 by brackets 19, and the yarn package supports of the invention are carried by and secured to the cake board. The yarn package support comprises a circular base plate 20, preferably of

metal, although it may be of wood or any other suitable material. Apertured lugs 21 depend from the base plate 20 and rest on the board 18 to support the plate in spaced parallel relationship with the board. Bolts 22 pass through the apertures in the lugs 21 and secure the base plate to the cake board.

The relatively movable two-part arbor 23-24 of the yarn package support is operatively mounted on the base plate 20. The relatively fixed or stationary part 23 is secured to the base plate by bolts 25, and the relatively movable part 24 is mounted between parallel guides 26 in the base plate. The parts 23 and 24 have a cylindrical outer contour, the circumferential periphery of which is slightly less than half the circle, so that the effective operating contour of the two parts is generally elliptical in each of their limiting operative positions (i. e. contacting, Fig. 4, and most remote from one another, Fig. 5), with the longer axis of the elliptical contour of one position (Fig. 4) at right angles to the longer axis of the elliptical contour of the other position, wherefore the effective operating contour of the two parts is substantially circular through a short range of their intermediate operative positions. The parts 23 and 24 may advantageously be molded of Bakelite or other suitable plastic material, or may be made of metal, wood or hard rubber.

The movable arbor part 24 has a transverse and vertically elongated recess or opening 27 formed therein (Figs. 1 and 3). A bell crank lever 28, pivoted on a pin 29 secured to a bracket 30 depending from the board 18, has its upper arm extending through a slot 31 in the board, and its other (lower) arm extending outwardly in front of the yarn package support. The end of the upper lever arm extends into the recess 27 of the movable arbor part 24, and is provided with a slot 32 through which extends a pin 33 secured in the opposite side walls of the recess. The lower lever arm is provided with a foot treadle 34.

A coiled tension spring 35 is attached at one end to the upper lever arm, above the board 18, and has its other end attached to an eye bolt 36 secured to and projecting above the board 18. A guard 37 covers the spring 35. The spring 35 is so formed that its tension, and hence the force exerted to pull the upper lever arm toward the main frame 17 (i. e. towards the right in Fig. 1), increases substantially as the upper lever arm is moved away from the frame (i. e. towards the left in Fig. 1).

In practicing the invention, the operator depresses the foot treadle 34 and thereby causes the upper lever arm to move the arbor part 24 into its contacting position with the cooperating arbor parts 23 (Figs. 2 and 4). The unsupported package or cake of yarn 10, covered with the customary protective fabric stocking 10', is then placed on the arbor, whereupon the operator releases the foot treadle. The spring 35 now acts to pull the movable arbor part 24 away from the stationary arbor part 23, thus causing the arbor to tightly grip the inside surface of the yarn package. The stocking 10' is then unwrapped from outside the yarn package and the top part of the stocking is tucked within the open top of the arbor, and the lower part of the stocking is folded around and under the base plate 20, as shown in Fig. 1. A circular cap 38 is inserted in the open top of the expanded arbor and acts as a balloon guide during unwind-

ing. Winding-off is then started by threading a single thread of the yarn package through the guides 13 and 14, tension device 16 and onto the cone winding spindle 12.

5 The maximum tension of the spring 35 is exerted to the beginning of the unwinding operation, when the wall of the yarn package is thickest. As the wall of the yarn package becomes thinner, the arbor expands because of the decreased restraining effect of the yarn package, and simultaneously the tension of the spring 35 correspondingly decreases. Thus, the greatest pull of the spring on the movable arbor part is exerted at the commencement of unwinding, and this pull gradually and progressively decreases as the unwinding operation proceeds.

10 In order to limit the expansion of the two-part arbor, a stop-motion device is preferably provided. In the drawings, this device is shown as a wedge-shaped plate 39 secured to the depending front flange of the cake board 18 by a bolt 40 extending through a slot 41 in the plate. As the arbor expands, in unwinding, the foot treadle 34 rises until it contacts the inclined lower edge of the plate 39, thereby limiting further movement of the movable arbor part 24. By means of the bolt 40 and slot 41, the point of contact of the foot treadle with the inclined lower edge of the plate can be varied to suitably adjust the limit of expansion of the arbor. In the absence of some means for limiting the expansion of the arbor, the last few wraps of yarn may be objectionably strained or stretched, thereby altering or even impairing the quality of the corresponding lengths of yarn.

15 The characteristic feature and advantage of the invention is that the two-part arbor presses tightly and effectively against the inside surface of the yarn package at all stages in the unwinding operation, but with a force that progressively decreases as the annular thickness of the yarn package decreases. Thus, the tension of the spring 35 keeps both parts of the arbor always tightly in contact with the inside of the yarn package, the stronger pull of the spring being exerted at the beginning of the operation, and as the yarn is wound off and the thickness of the package becomes thinner and the resistance to expansion consequently less, the spring itself exerts a correspondingly diminished pull. This is a particularly important feature of the invention, since it is desirable to ease the force exerted against the inside of the yarn package as the package thins out, while at the same time maintaining just sufficient tension to insure secure holding of the package to prevent sloughing off, thus insuring complete unwinding of the yarn and consequently no waste, with no injury to the yarn and with a minimum of breakages.

20 I claim:

1. A support for a yarn package comprising a base, a two-part arbor adapted to be surrounded by and to tightly grip a yarn package, one part of said arbor being secured to said base and the other part of the arbor being arranged to slide on the base into contact with and away from the part of the arbor secured to the base, and tension means normally biasing the sliding part of the arbor to its operative position most remote from the other part of the arbor.

2. A support for a yarn package comprising a base, an arbor mounted on said base and adapted to be surrounded by and to tightly grip a yarn package, said arbor having a relatively fixed member secured to said base and a cooperating mov-

able member slidably mounted on said base for movement towards and away from said fixed member, a lever operatively connected to said movable member for moving it towards said fixed member, and tension means for moving said movable member away from said fixed member with a force that progressively decreases as the distance between the members increases.

3. A support for a yarn package comprising a base, a two-part arbor operatively mounted on said base and adapted to be surrounded by and to tightly grip the interior surface of a substantially annular yarn package, one part of said arbor being secured to said base and the other part of the arbor being arranged to move towards and away from the part of the arbor secured to the base, guide means operatively attached to the said base for guiding the movable part of the arbor as it moves towards and away from the part of the arbor secured to the base, a spring normally biasing the moving part of the arbor to its operative position most remote from the other part of the arbor, the force exerted upon said moving part by said spring progressively decreasing as the distance between the two parts of the arbor increases, and means for moving said moving part towards the other part of the arbor and against the tension exerted by said spring.

4. A support for a yarn package comprising a base, a two-part arbor operatively mounted on said base and adapted to be surrounded by and to tightly grip the interior surface of a substantially annular yarn package, one part of the arbor being secured to said base and the other part of the arbor being arranged to slide in guides towards and away from the part of the arbor secured to the base, each of said arbor parts having a cylindrical outer contour with a circumferential periphery slightly less than half the circle, tension means normally biasing the sliding part of arbor to its operative position most remote from the other part of the arbor with a force varying inversely as the distance between the two arbor parts, and means for moving said sliding part to-

wards the other part of the arbor and against the force exerted by said tension means.

5. A support for a yarn package comprising a base, an arbor mounted on said base and adapted to be surrounded by and to tightly grip a yarn package, said arbor having a relatively fixed member secured to said base and a cooperating movable member slidably mounted in guides on said base for movement towards and away from said fixed member, a lever operatively connected to said movable member for moving it towards said fixed member, tension means for moving said movable member away from said fixed member with a force that progressively decreases as the distance between the members increases, and adjustable means cooperating with said lever for limiting the movement of said movable member away from said fixed member.

6. A support for a yarn package comprising a base, a two-part arbor operatively mounted on said base and adapted to be surrounded by and to tightly grip the interior surface of a substantially annular yarn package, one part of said arbor being secured to said base and the other part of the arbor being arranged to slide on the base towards and away from the part of the arbor secured to the base, each part of said arbor having a cylindrical outer contour of such circumferential periphery that the effective operative contour of the two parts of the arbor is elliptical in both of their limiting operative positions but with the longer axis of the elliptical contour of one position at right angles to the longer axis of the elliptical contour of the other position, a spring normally biasing the sliding part of the arbor to its operative position most remote from the other part of the arbor, the force exerted upon said sliding part by said spring progressively decreasing as the distance between the two parts of the arbor increases, and means for moving said sliding part towards the other part of the arbor and against the tension exerted by said spring.

JAMES BURREL PARKER.
